CLAIM

The ornamental design for a light therapy device, as shown
and described.

DESCRIPTION

FIG. 1 is a front perspective view of a light therapy device
showing the new design;

FIG. 2 is a bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof; and,

FIG. 9 is a rear perspective view thereof in a condition of
use. The broken lines depicting the applicators and cords are
for environmental purposes and form no part of the claimed
design.

The even-length broken lines shown in the drawings illus-
trate portions of the light therapy device that form no part of
the claimed design. The broken lines of uneven length
illustrate the boundary of the claimed design and form no
part thereof.
